SEPARATION OF OIL AND WAX

Harold S. Blisard, Springfield, Elmer H. Smith and Richard K. Rockstroh, Media, and Jack A. Guthrie, Springfield, Pa., assignors to Sun Oil Company, Philadelphia, Pa., a corporation of New Jersey

Filed Feb. 16, 1956, Ser. No. 565,839

3 Claims. (Cl. 208—33)

This invention relates to the separation of oil and wax, and particularly relates to a process for dewaxing petroleum mineral oils and deoiling petroleum waxes.

United States Patent No. 2,726,990 describes a process for the separation of oil and wax. According to the process, petroleum fractions of different boiling ranges are separately dissolved in solvents therefor and the solutions separately chilled to precipitate wax. The so-formed slurries are then admixed and the wax separated from the admixture by filtration. Also, according to the process, the mixing of the two fractions at any point prior to the chilling operation should be avoided.

It has now been found that by admixing a relatively small, critical quantity of the lower boiling fraction with the higher boiling fraction prior to chilling, filtration rates for the separation of wax from oil are markedly improved and other advantages are obtained. It is essential, however, that the two fractions, after the addition of a small amount of the lower boiling fraction to the higher boiling fraction, be separately chilled and that the slurries resulting from the chilling be admixed prior to filtration.

In an embodiment of the process of the invention, topped crude oil is distilled to produce a distillate and a residual fraction. These fractions are advantageously refined to remove undesirable constituents, such as aromatics and asphalts. After refining, a small quantity of the distillate fraction is introduced into the residuum fraction. The quantity of the introduced fraction must be within the range of from 5% to 20% by volume based on the quantity of the residuum fraction. Solvent having a preferential solvent power for the oil is then advantageously added to both the distillate and residuum fractions to form solutions thereof, and the so-formed solutions separately chilled to a temperature sufficient to precipitate a major proportion of the wax therein. The chilled slurries are admixed and wax is separated from the mixture by filtering.

By introducing a small quantity of the distillate fraction into the residuum fraction, it has been found that the filtration rates for separating the precipitated wax from oil are improved so that, in effect, the capacity of the filter is substantially increased. This results in a large increase in the quantity of oil and wax which can be produced from the same equipment.

Attention is now directed to the accompanying flow diagram which illustrates a preferred embodiment of the present process. Crude oil feed is introduced through line 1 into vacuum still 2. The crude oil may be subjected to a prior distillation (not shown) for removal of light hydrocarbons, such as gasoline, naphtha and gas oil. Light hydrocarbons, or remaining light hydrocarbons, such as gas oil, are removed from still 2 through line 4. A distillate fraction boiling in the lubricating oil range is removed from still 2 through line 5, and a residual stream is removed from still 2 through line 6. It is usually desirable to subject each stream to a refining operation, preferably solvent extraction, to remove aro-

2

matics from the distillate stream, and aromatics and asphalt from the residual stream, as indicated by 8 and 9, respectively. After the refining step a small quantity of the distillate fraction is introduced through line 7 into the residual fraction. A solvent is then introduced through line 10 and admixed with the distillate fraction in line 11, the temperature at some stage of admixing being sufficient to obtain dissolution of the distillate fraction in the solvent. Solvent is introduced through line 12 and admixed with the mixture of distillate and residual fractions in line 14, the temperature at some stage of admixing being sufficient to obtain dissolution of the mixture of fractions in the solvent. If necessary or desirable, a separate vessel may be provided to obtain complete dissolution of each fraction. The solution of the distillate fraction passes from line 11 to chiller 15 wherein wax crystals are precipitated to form a slurry. The solution of the residual fraction passes from line 14 into chiller 16 wherein wax is precipitated to form a slurry. The so-formed slurries pass from chillers 15 and 16 through lines 18 and 19, respectively, are admixed in line 20 and passed to filter 21. If desired, the small quantity of distillate can be introduced into the residual fraction after the introduction of solvent as shown at 12, but it is essential that the addition be made prior to chilling as shown at 16.

Filtration is advantageously accomplished by means of a rotary vacuum filter having provision for supplying wash liquid to the filtered wax and subsequent drying by suction. Separate continuous take-offs for the washed wax cake, used wash, and filtrate are provided. Wash liquid is applied to the filtered wax cake through line 22; used wash passes out through line 24 and may be recycled preferably after stripping to remove dissolved oil and any wax that may be present. Filtrate is removed through line 25 and passed to a distillation unit (not shown) in order to separate the solvent, which is recycled to the process, from the oil. The wax cake is removed through line 26. Filtration may be accomplished by means other than a rotary vacuum filter, such as by filter pressing, and good results obtained therewith. Valves, pumps, heat exchangers, and the like, the location and operation of which will be apparent to those skilled in the art, have been omitted from the diagram.

The dewaxed oil after separation of solvent is subjected to distillation in order to form the desired fractions.

The solvent employed should have a preferential solvent power for the oil, should dissolve wax at relatively high temperatures, and precipitate wax at relatively low temperatures. A mixture of a wax anti-solvent, such as methyl ethyl ketone, and an oil solvent, such as benzene, gives good results, and a mixture thereof containing approximately equal parts by volume is the preferred solvent, but either of these components may be replaced, in whole or in part, by other materials. For example, other ketones such as methyl butyl ketone or acetone may be substituted for methyl ethyl ketone, and toluene may be substituted for all or a part of the benzene. It is preferred to employ the same solvent for dissolving each fraction from the initial distillation, since recovery of solvent after admixing the slurries and filtering is less difficult than if different solvents are employed. The wash liquid for the wax cake is also preferably the same as the solvent, and should be cooled to approximately the same temperature as the temperature of filtration before applying to the wax cake. In the event that either the distillate or residual slurry, or both, is too thick to obtain easy flow to the filter, additional chilled solvent may be added thereto.

In a preferred method of operating the process of the

present invention, two fractions, a distillate fraction and a residual fraction, are prepared by the initial distillation. The distillate fraction usually has a boiling range of from about 650 to 900° F. at atmospheric pressure. The residual fraction usually has a boiling range of above 850° F. at atmospheric pressure. An overlapping of the distillate and residual boiling range has no deleterious effects. The process of the present invention may also be employed to dewax oil from two distillate fractions of different boiling range. Such distillate fractions may be successive fractions, such as two fractions having boiling ranges of from 650 to 725° F. and from 725 to 900° F., or fractions not adjacent in boiling range, such as two fractions having boiling ranges of from 600 to 700° F. and from 750 to 900° F. The distillate fractions, or the distillate and residual fractions, will generally be from the same distillation operation, but fractions of different boiling ranges obtained from separate sources may be employed. The process of the present invention may thus be employed to separate wax and oil contained in wax-oil mixtures having different boiling ranges. This is accomplished, as above described, by introducing a small quantity of the lower boiling wax-oil mixture into the higher boiling wax-oil mixture, and separately treating each wax-oil mixture as follows: dissolving the mixture in a solvent at a temperature sufficient to obtain dissolution, chilling the solution to produce wax crystals and form a slurry, combining the separately formed slurries and filtering the combined slurries. In chilling the solutions to produce wax crystals, at least 10% of the wax present in each fraction must be precipitated before combining the slurries. The filtrate from this operation may be separated into the desired oil products by distillation. In this final distillation, the oil products may be separated at the same temperature and pressure as the initial fractions. The process, however, is not so limited; any desired oil fraction or fractions may be obtained.

It is of advantage in some instances to employ a small quantity of a material known to assist in a filtering operation. The material selected, however, should not deleteriously affect the wax production, or should be readily separable from the wax. The quantity of such material should not be above about 0.1% by volume of the oil charged and is usually within the range of from 0.01 to 0.08% by volume of the oil charged. Such added material, when used, can be introduced prior to, or after the chillers in either or both of the low boiling or high boiling fraction. Such addition is especially advantageous in decreasing the quantity of oil separated with a slack wax on the filter, and in decreasing the quantity of wash liquid required in the filtration operation. Materials that are commercially available and are known to assist the separation of wax from oil give good results. Such materials may be condensation products, polymerization products, extracts from high boiling petroleum fractions, and the like, such as described in United States Patents 2,081,519, 2,178,328, and 2,722,499.

Good results are obtained in the process of the invention when the ratio of distillate slurry to residual slurry, including the added distillate, is from 1:20 to 20:1, which ratio may be determined from the volumes of the distillate and residual fractions, or from their raffinates if refined as in the examples herein given, or from the wax contents thereof.

The foregoing description of the process of the present invention has been directed principally to the dewaxing of petroleum oils. The present process may also be employed where the primary object is to deoil wax to prepare wax products. For example, the wax precipitate obtained as above described, or a slack wax containing a relatively large quantity of oil, say from about 10% to 60%, may be deoiled by subjecting the oily wax to a series of steps as above described. For example, a slack wax containing about 30% oil is subjected to vacuum

distillation to prepare a distillate fraction and a residual fraction. From 5% to 20% by volume of the distillate fraction, based on the residual fraction, is added to the residual fraction. The fractions are separately dissolved in a solvent at a temperature sufficient to obtain dissolution. The solvent is advantageously the same as above described for deoiling wax. The solutions are separately chilled to precipitate wax to form wax slurries. The slurries are admixed and the combined slurries filtered. The separated oil-free wax is distilled to produce the desired products.

In this embodiment of the present process, the same advantages as described for dewaxing oil are obtained, namely, an enhanced rate of filtering wax from oil, a decrease in the quantity of solvent and wash liquid required with a corresponding decrease in refrigeration requirements, and improved separation of wax from oil.

Example I

In order to show the advantages of the process of the invention by specific embodiments, the present process was compared with the process of United States Patent Number 2,726,990.

According to the process of the invention of said patent, 520 barrels per day of a petroleum distillate fraction and 960 barrels per day of a residual fraction were processed, using 1100 barrels per day of wash liquid, to produce 1,180 barrels per day of oil. This constituted an 80% yield of oil, the oil content of the wax product was 15%. In this operation, the distillate and residual fractions were separately refined, dissolved in solvents, chilled to about -10° F. and admixed only after chilling to precipitate wax for subsequent filtration.

This operation was substantially repeated, except that about 96 barrels per day of distillate fraction were admixed with the residual fraction, prior to dissolving the fractions in solvent for subsequent chilling to about -10° F., while maintaining the quantity of the distillate fraction passing to its separate chilling at 520 barrels per day. It was found that by this operation, the filtration rate, which was the limiting factor in the prior operation, easily handled the increased through-put so that about 1,260 barrels of oil per day were produced and the filtration rate was not the limiting factor in the process i.e., an even greater through-put could be maintained if desired. In the process, using the same quantities of solvent and wash liquid, the oil content of the wax product is substantially as in the prior process, namely, about 15%. It was found that the total amount of wash liquid could be reduced to 800 barrels per day with an increase in oil content of the wax to only about 20%.

Example II

In order to show the critical nature of the quantity of the distillate fraction added to the residual fraction prior to chilling, and the advantages of using a filter aid, varying quantities of distillate fraction were introduced into the residual fraction, and from about 0.026 to 0.7% of a filter aid added to the residual fraction. The filter aid was a commercially available hydrocarbon material derived from the high boiling petroleum fraction. The following results were obtained:

Adding 3.5% by volume of distillate fraction (based on the quantity of the residual fraction) to the residual fraction resulted in no measurable increase in the rate of filtration, i.e., the total through-put was not increased. Adding 5% of the distillate fraction to the residual fraction resulted in a marked increase in the rate of filtration which increased so that when 7% of distillate was added to the residual fraction, an additional 50 barrels per day of charge was processed. Addition of even larger quantities proved advantageous and the addition of 11% of distillate to the residual fraction resulted in an increase in the filtration rate so that an additional 150 barrels per day of charge was processed. A still further increase in

the filtration rate is observed up to about 15% of distillate in the residual fraction. However, introducing more than 20% of the distillate fraction into the residual fraction results in deleterious effects including an increase of the oil content of the slack wax product and a decrease in the rate of slack wax production. In all of the runs having from 5% to 20% by volume distillate in the residual fraction, the oil content of the wax remained at about 15%. However, when the filter aid is omitted, the oil content of the slack wax increases to about 20%.

The invention claimed is:

1. Method of separating wax from oil which comprises: (A) distilling a mixture of wax and oil to form at least two wax-oil fractions having different boiling ranges, (B) admixing a portion of the lower boiling fraction prior to any dewaxing thereof, with the higher boiling fraction, said portion being from 5% to 20% by volume based on the higher boiling fraction, (C) dissolving the remainder of the lower boiling fraction in a solvent and chilling the resulting solution to precipitate at least 10% of the wax present whereby a slurry is formed, (D) dissolving the admixture of lower boiling fraction and higher boiling fraction in a solvent and chilling the resulting solution to precipitate at least 10% of the wax present whereby a slurry is formed, (E) admixing said slurries, (F) filtering the admixed slurries to separate said precipitated wax from oil and solvent, and (G) separating oil from solvent.

2. Method of separating wax from oil which comprises: (A) distilling a mixture of wax and oil to form at least two wax-oil fractions having different boiling ranges, (B) admixing a portion of the lower boiling fraction prior to any dewaxing thereof, with the higher boiling fraction, said portion being from 5% to 20% by volume based on the higher boiling fraction, (C) dissolving the remainder of the lower boiling fraction in a solvent and chilling the resulting solution to precipitate at least 10% of the wax present whereby a slurry is formed, (D) dissolving the admixture of lower boiling

fraction and higher boiling fraction in a solvent and chilling the resulting solution to precipitate at least 10% of the wax present whereby a slurry is formed, (E) admixing said slurries in a volume ratio of slurry from the lower boiling fraction to slurry from the higher boiling fraction of from 1:20 to 20:1, (F) filtering the admixed slurries to separate said precipitated wax from oil and solvent, and (G) separating oil from solvent.

3. Method of dewaxing petroleum oil which comprises:

(A) distilling wax-bearing petroleum oil to form a distillate wax-oil fraction boiling in the range of from about 700° F. to about 850° F. at atmospheric pressure and a residual wax-oil fraction boiling above about 850° F. at atmospheric pressure, (B) admixing a portion of the distillate fraction, prior to any dewaxing thereof, with the residual fraction, said portion being from 5% to 20% by volume based on the residual fraction, (C) dissolving the remainder of the distillate fraction in a solvent and chilling the so-formed solution to a temperature of about -10° F. to precipitate at least 10% of the wax present whereby a slurry is formed, (D) dissolving the admixture of distillate and residual fractions in a solvent and chilling the so-formed solution to a temperature of about -10° F. to precipitate at least 10% of the wax present whereby a slurry is formed, (E) admixing said slurries, (F) filtering the admixed slurries at a temperature of about -10° F. to separate precipitated wax from oil and solvent, and (G) separating oil from solvent.
